UNITED STATES PATENT OFFICE.

GLENN B. CULBERTSON, OF INDIANAPOLIS, INDIANA, ASSIGNOR TO ARTHUR E. STRICKLAND, OF INDIANAPOLIS, INDIANA.

ADJUSTABLE STAND.

Application filed March 7, 1927. Serial No. 173,427.

This invention relates to a bed stand for reading and writing purposes.

The chief object of the invention is to provide a stand that can be used for reading and writing purposes while lying or seated in bed or seated in a chair.

The chief feature of the invention consists in the universal adjustability of the stand or platform.

10 Another feature of the invention consists in the knockdown or collapsible arrangement of the several parts.

Still a further feature of the invention consists in the simplification of the several 15 parts and the reduction thereof to a minimum number and these of like character so that they may be formed from a minimum number of dies.

20 The full nature of the invention will be understood from the accompanying drawings and the following description and claims.

In the drawings Fig. 1 is a front view 25 thereof.

In the drawings 10 indicates a platform and the same supports compressible clamps of which four are shown. The clamps comprise a clamping portion 11, the free end 30 terminating in a loop 12 and the same is connected to a supporting portion 13 by a loop 14 and said supporting portion has an eye 15 by means of which the same is pivotally anchored to the back of the platform by the screw 16. The base 13 is extended beyond 35 the anchorage as shown and constitutes a bearing for increasing the pressure exerted by the clamping portion 11. Any other form of leaf clamps may be mounted on the platform as desired. Each side of the platform 40 is provided with a rail 17 and herein the same is on the back. Said rails support pivot forming means which in the present invention, is shown as an elongated threaded bolt 45 18 having the head 19 and adapted to receive the clamping nut 20 at the opposite end.

The framework supporting the pivot and 50 adjustably supporting the platform consists of a pair of triangular wire members, the same being inclined, as shown in Fig. 1, for forming an A-frame arrangement. Each side portion of the framework consists of a single wire having the base 21 and the 55 two upwardly and inwardly directed exten-

sions 22 each terminating in an eye 23 receiving the bolt 18. Adjacent the junction of each side 22 with the base 21 is an eye socket 24. The two triangular side frames have their eyeleted ends secured in spaced 60 relation by the rod 18, said ends bearing on washers 25 adjacent the side rails 17 of the platform 10. The lower portions of the triangular side frames are also connected together in spaced relation as follows: An 65 arch member, wire or rod 26 has a semi-circular loop 27 at each end and each eye 24 is adapted to receive one of the semi-circular loops 27, as shown. Spreading movement of the side frames outwardly at the base is prevented by the eye 24 engaging the junction 28 of the arch member and loop 27 and inward movement of the arch member 26 is prevented by engagement of the extension 29 with the portion of the side frame immediately adjacent the eye 24. The resultant construction, therefore, is that the entire framework is relatively rigid when in assembled relation.

To collapse or knockdown the same, the 80 eyes 23 are released from the pivot forming projecting ends of the bolt 18 or its equivalent, and the side frames are turned inwardly towards each other. This permits the free end 29 to clear the portion adjacent 85 the eye 24 and that thus permits the arch member 26 to be tilted inwardly a sufficient amount so that the several members may be readily detached if desired. If it is desired to have said members permanently connected 90 together a suitable arrangement may be provided between the junction of the inclined sides and base of the triangular framework with the adjacent end of the arch member.

Fig. 2 illustrates a position in which a 95 book is clamped to the platform and the same is held in substantially inverted position so that the reader therebeneath on a bed or the like can read with perfect ease and comfort. If the stand is to be used with a 100 chair, or by one who is sitting up in bed, the platform will be positioned about ninety degrees from that shown in Fig. 1. The framework is so arranged that it substantially straddles the person whether they be seated in a chair, or seated in bed or lying in bed and provides ample clearance. Releasing the clamping tension of nut 20 permits the standard 10 to be tilted into any 105 desired position, whereupon threading of the 110

nut will clamp the parts so that the standard will be maintained in the adjusted position.

The invention claimed is:

1. A straddle type framework for a stand of the character described, including a pair of substantially triangular side frames, and a pair of arched members connecting adjacent corners of the opposite sides of said triangular frames, said arched members being otherwise independent of each other and providing a relatively clear space therebeneath.
2. A straddle type framework for a stand of the character described, including a pair of substantially triangular side frames, arched means connecting adjacent corners of

the opposite sides of said triangular frames, each frame adjacent the lower corner thereof including a socket, and each arch member including a complementary engaging end receivable by said socket and permitting collapsible positioning therebetween when desired. 20

3. A device as defined by claim 2, characterized by each side frame comprising a single member having the sockets formed in the base angles and the free ends being positioned adjacent each other and formed for a common anchorage. 25

In witness whereof, I have hereunto affixed my signature. 30

GLENN B. CULBERTSON.

CERTIFICATE OF CORRECTION.

Patent No. 1,671,231.

Granted May 29, 1928, to

GLENN B. CULBERTSON.

It is hereby certified that the above numbered patent was erroneously issued to Arthur E. Strickland, of Indianapolis, Indiana, as assignee of entire interest in said invention, whereas said patent should have been issued to the inventor said Culbertson and Arthur E. Strickland, of Indianapolis, Indiana, said Culbertson being assignee of one-half interest only in said invention, as shown by the records of assignments in this office; and that the said Letters Patent should be read with this correction therein that the same may conform to the record of the case in the Patent Office.

Signed and sealed this 19th day of June, A. D. 1928.

(Seal)

M. J. Moore,
Acting Commissioner of Patents.
